UNITED STATES PATENT OFFICE.

GEORGE H. FORSYTH, OF CHICAGO, ILLINOIS, ASSIGNOR TO THE FORSYTH BROTHERS COMPANY, OF SAME PLACE.

CURTAIN-FIXTURE.

SPECIFICATION forming part of Letters Patent No. 625,753, dated May 30, 1899.

Application filed March 22, 1899. Serial No. 710,063. (No model.)

To all whom it may concern:

Be it known that I, GEORGE H. FORSYTH, of Chicago, in the county of Cook and State of Illinois, have invented certain new and useful Improvements in Curtain-Fixtures, of which the following is a specification.

This invention relates to an improvement in fixtures for spring-actuated curtains or shades.

10 The object of the invention is to provide a fixture of this class which shall be adequate to hold the shade or curtain against the pull of the shade-roller spring at any adjusted position and to enable the curtain to automatically 15 right itself when the shade-stick is thrown into an oblique position by accident or careless manipulation. Self-righting holding mechanisms of this general character have been heretofore provided, as, for example, in the patent to Forsyth and Forsyth, No. 559,446, dated May 5, 1896. In said patented construction the automatic self-righting is effected by providing 20 separated bearings or contact-points of diverse frictional holding power, arranged in such relation to each other that when the margin of the shade is moved from a horizontal to an oblique position the bearing-point of least resistance is engaged and the bearing-point of greater frictional holding power wholly or partially withdrawn from contact. The commercial form of said invention embodies heads mounted upon the ends of the shade-stick and having antifriction-rollers at their extremities and friction shoes or blocks between the rollers. This type of fixture is known as 35 the "roller-tip" fixture.

My present improvement has for its object to attain the same desirable results accomplished by the automatic self-righting fixtures above described, but in a different manner.

My invention comprises a shade-stick provided at its ends with rollers or wheels arranged in pairs or in series and rotatably mounted in peripheral contact, their centers of rotation being variable with relation to each other, so that when the stick is in a normal position or substantially parallel to the shade-roller the wheels or the rollers impinge upon the bottoms of the grooves and contact with each other to such extent as to prevent or diminish their rotation, thus causing said

wheels or rollers to become friction-surfaces, which hold the shade or curtain in the adjusted position. When, however, the lower margin of the shade or curtain and the shade-stick are moved into an oblique or abnormal position, one of the bearings is released and the wheels or rollers are released from further frictional interlocking contact and become antifriction-surfaces, which enable the curtain or shade to automatically self-right.

My invention may be embodied in a variety of mechanical constructions and combination of parts, some of which are shown in the accompanying drawings, in which—

Figure 1 is an elevation showing a fragment or corner of the curtain or shade, the end of the carrying-tube in section, and the shade-stick, its operating-spring, and the head and wheels in elevation. Fig. 2 is a front or face view of the head carrying the rollers or wheels. Fig. 3 is a view similar to Fig. 1, except that the interlocking wheels are arranged in pairs at the extremities of the head. Fig. 4 is a face view of the head shown in Fig. 3. Figs. 5 and 6 show a short head with a single pair of wheels, and Figs. 7 and 8 are intended to illustrate the principle of operation of the devices shown in Figs. 1 to 4, inclusive.

In the drawings let 10 represent the shade or curtain, which is provided with a pocket carrying the metal tube 11, within which is mounted the sliding rod 12. 13 is the spring normally thrusting said rod outwardly by engaging with a sleeve 14 fixed thereon. The extremity of the rod carries the head 15, which is adapted to travel within the groove in the frame or casing of the window and which is represented conventionally by the line 16. These heads, one of which is mounted at each end of the shade-stick, in connection with the grooves, form in the usual way the guides to prevent the curtain from flapping.

In Fig. 1 a head is shown having antifriction-rollers in its extremities, said rollers being marked 17 and being intended to assist in the self-righting of the fixture. The friction devices, which hold the head in its adjusted positions, comprise rollers or wheels 18, these being arranged either in pairs or in series, with their peripheries in contact. As shown in Figs. 1 to 4, inclusive, the rollers

are mounted upon pins 19, passing transversely through the side walls of the head 15. The rollers or wheels 18 have enlarged apertures 20, through which the pins 19 pass. If 5 now the curtain-fixture be in the position shown in Fig. 1, the wheels or rollers projecting slightly beyond the faces of the head and contacting with the surface 16, the peripheries of the rollers will jam or be held 10 in interlocking frictional contact, so as to furnish the requisite friction to hold the curtain in the adjusted position. If, however, in operation the shade-stick be tilted or placed 15 in an abnormal position, obviously one of the rollers will be partially withdrawn from contact with the bottom of the groove, and as soon as its bearing is released the roller remaining in contact will turn freely, thus permitting the curtain or shade to right itself. 20 The principle of this operation may be explained by considering the fact that a pair of rollers thus arranged have three bearing-points or points of contact, each roller contacting with the other and each separately 25 contacting with the bottom of the groove. Now so long as pressure is applied at these three points of contact the rollers will be restrained. As soon as pressure is relieved between one of the rollers and the bottom of the 30 groove then the roller thus freed has no effect in restraining the free rotation of the one left in contact, and therefore the roller remaining in contact revolves freely, assisting the righting of the fixture, while the roller 35 removed from contact also revolves freely, but out of contact.

I have described the operation of the construction shown in Figs. 1 and 2 without reference to the antifriction-rollers 17 in the extremities of the heads. In order to make the 40 device sensitive, I prefer to employ the elongated heads shown and to provide the antifriction-rollers 17 in the ends thereof. When they are used, if the shade-stick be tilted the 45 antifriction-roller in the extremity of the head will be brought into contact with the bottom of the groove and will assist in the self-righting of the fixture. When this form of construction is used, it may be considered 50 as an improved form of roller-tip fixture, in which the antifriction-rollers at the extremities assist in the self-righting, while the interlocking rollers or wheels form a yielding friction located intermediate the antifriction- 55 wheels. This form of device will be more sensitive than that in which a fixed friction-block is employed and less objectionable in use than another known construction wherein a pivoted friction shoe or block is employed, 60 because in my construction both the friction and the antifriction surfaces or devices are curved surfaces instead of plain surfaces and present no ends or edges to catch or engage the surfaces with which they contact. 65 In the construction shown in Figs. 3 and 4 the elongated heads are employed; but the interlocking rollers are arranged in pairs at

the extremities of the heads and afford when the stick is parallel with the shade-roller interlocking friction-surfaces which will restrain the curtain against the pull of its spring-roller, and when the stick is tilted the pair at one end will be withdrawn from contact and the pair at the opposite end will be freed, so as to become antifriction instead of 75 friction devices.

In the construction shown in Figs. 5 and 6 a short head is employed with a single pair of rollers, and said rollers instead of having enlarged apertures have journals, for which 80 enlarged bearings are provided, preferably in the shape of converging slots 21, formed in the side walls of the head. These converging slots permit the rollers to jam together when the stick is in a horizontal position and when 85 it is tilted permit the rollers to separate, thus releasing them from interlocking contact. Figs. 5 and 6 show the operation of the rollers when provided with journals moving in converging slots, and Figs. 7 and 8 show the 90 operation of the rollers having enlarged apertures and mounted on fixed axles. The principle of operation is, however, the same in both cases, and either construction may be employed with the forms of head shown. 95

While I have shown the rollers arranged in pairs, it is of course within the scope of my invention to employ three or more rollers mounted in peripheral contact. Since two illustrate the principle of my invention, I 100 have deemed representation of a series unnecessary. I have shown the rollers or wheels mounted in boxes carried upon the ends of rods constituting a part of the shade-stick and having outwardly-thrusting springs. The 105 rods may be omitted and the shanks of the heads inserted in and carried by the tubes and the springs bear directly on the heads. The rods may, if used, be provided with pendants for retracting them in operating the fixture, or the curtain may be manipulated by grasping its lower margin and pushing it up or pulling it down.

Without limiting myself to precise details of construction or correlation of parts, except 115 as hereinafter particularly pointed out, I claim—

1. A curtain-fixture of the class described, comprising a shade-stick having heads provided with a plurality of rollers or wheels 120 having peripheral contact with each other, and adapted to have both rotary and bodily movement and to contact with the window-frame, whereby, when the stick is in a horizontal position, the peripheral contact of the 125 rollers causes them to serve as friction devices, and when the stick is tilted, the peripheral friction is diminished to permit one or more of the rollers or wheels to become antifriction devices, substantially as described. 130

2. A curtain-fixture of the class described, comprising in combination a curtain-stick, heads at the ends of the stick, each of said heads having a plurality of rollers or wheels

having apertures, pins or axles carried by the heads and extending through said apertures, said pins or axles being of less diameter than said apertures and said wheels or rollers being adapted when in contact with the window-frame to have peripheral contact with each other to constitute friction-surfaces, and when the stick is tilted to constitute antifriction-surfaces, substantially as described.

5 10 3. A curtain-fixture of the class described, comprising in combination a curtain-stick

having elongated heads at its ends, rollers or wheels mounted in pairs toward the ends of said heads in peripheral contact, and adapted to have both rotary and bodily movement and 15 to contact with the window-frame, substantially as described.
